UNITED STATES PATENT OFFICE.

CHARLES V. JAMESON, OF CHICAGO, ILLINOIS.

PNEUMATIC ACTION FOR MUSICAL INSTRUMENTS.

1,353,753.

Specification of Letters Patent. Patented Sept. 21, 1920.

Application filed October 10, 1917. Serial No. 195,666.

To all whom it may concern:

Be it known that I, CHARLES V. JAMESON, a citizen of the United States, residing at Chicago, in the county of Cook and State 5 of Illinois, have invented new and useful Improvements in Pneumatic Actions for Musical Instruments, of which the following is a specification.

This invention relates more particularly 10 to the type of pneumatic actions known as "unit actions", in which the controlling valves and associated parts of each striker pneumatic constitute a detachable unit which is separate and distinct from the remaining units, facilitating assemblage of 15 the parts and repair and renewal of the valves.

One of the objects of my invention is to increase the rigidity of the wind chest in 20 such a manner as to render it practically self-bracing, thereby dispensing with the customary braces and correspondingly simplifying its construction and reducing its cost of production.

25 Further objects are to render all parts of the action readily accessible, to produce a novel construction which affords comparatively large air passages not liable to become choked by dust and lint, and to combine with the action simple and compact regulating devices to which access can be easily had without removing or disturbing other parts of the action or instrument.

In the accompanying drawings:

35 Figure 1 is a fragmentary front elevation of a wind chest containing the invention. Fig. 2 is a fragmentary rear elevation thereof. Fig. 3 is a transverse section of the action on line 3—3, Fig. 2, with some of the 40 parts omitted for clearness. Fig. 4 is a fragmentary front view, partly in section, of the channel-board. Fig. 5 is a rear view, partly in section, of one of the valve blocks. Fig. 6 is a sectional bottom plan view there- 45 of. Fig. 7 is a view of the hinged end of one of the striker-pneumatics.

Similar characters of reference indicate corresponding parts throughout the several views.

50 1 indicates the keys of a player piano, 2 the shank of one of the hammers of the piano action, 3 the wippen, 3^a the jack and 4 the sticker.

The frame or body of the wind chest 55 shown in the drawings comprises upright

end pieces or standards 5, a longitudinal base strip or board 6 connecting the lower portions of said standard and longitudinal upper strips 7, 8 and 9, connecting their upper portions. This frame may however be 60 of any other suitable construction.

In its general organization, the pneumatic action comprises a fixed upright longitudinal channel board 10, rows of striker pneumatics 11 mounted on the rear side of said 65 board, and corresponding rows of valve blocks or units 12 mounted on the front side of said board. These pneumatics are carried by horizontal channel boards or shelves 13 to the undersides of which their fixed 70 boards are glued or otherwise fastened, in the particular construction shown in the drawings. The upright channel board 10 is suitably fastened to the standards 5 and the strips 6 and 9 and is provided with longitudinal vacuum channels or chambers 14, one for each row of valve-blocks and the companion striker pneumatics. The several vacuum channels communicate at their ends with upright manifold passages 15 which 75 are connected with the usual main exhaust bellows, not shown, by one or more trunks 16, so that said channels 14 are constantly exhausted during the operation of the instrument. 85

The valve-blocks or units are detachably secured to the channel board 10 by screws 17 or other fastening means. These units may be of any suitable construction, but that shown in the drawings is preferred. Each 90 block contains a lower vacuum chamber 18 connected by a passage 19 with the corresponding vacuum channel 14 of the board 10, and an upper air or vent chamber 20 connected with the corresponding striker 95 pneumatic 11 by a channel 20^a extending transversely through said channel board and the corresponding shelf 13 above the companion passage 19. A vent port 21 connects the chamber 20 with the atmosphere. 100 The partition 22 of the block contains the vacuum port 23. Located in the upper valve-chamber is the usual duplex valve 24, the heads of which coöperate with the vacuum and vent ports 23 and 21 respectively, to open the one when the other is closed and thereby collapse or inflate the corresponding striker pneumatic 11, in a common manner. 25 indicates the customary valve-operating pouch or pneumatic ar- 110

ranged in the lower portion of the block, and 26 the tube leading from the corresponding duct of the tracker 27 to the chamber underneath the pouch.

5 In the preferred construction illustrated in the drawings, the striker pneumatics are directly in line with their companion valve blocks.

As shown, the channel board is a single member common to the various valve blocks and striker pneumatics. Being set vertically on edge and comparatively deep and narrow, it possesses the necessary strength and stiffness to avoid sagging or warping thereof. This channel board is thus practically self-bracing, doing away with the separate brace members or blocks required, for example, in pneumatic actions of the layer type and correspondingly reducing the 20 cost of the wind chest. At the same time, the valve units are readily accessible and detachable from the channel board. This construction also permits the use of air passages of sufficient area to guard against 25 choking of the action.

28 indicates the stickers of the pneumatic action each of which co-operates with the corresponding wippen 3. Each of these stickers is preferably bent from a single length 30 of wire. It has the usual button or collar 29 which is engaged by the movable board of the corresponding striker pneumatic. Under the projecting front portion of the wippen it is provided with a forward bend 35 or shoulder 30 adapted to actuate the same, and extending upwardly and forwardly from this shoulder is a stop or finger 31. This finger plays between a pair of adjustable stop members 32, 33, which determine 40 the stroke of the sticker 28 and its effect upon the piano-hammer, and the finger is guided in and held against displacement by a vertical guide-groove 31^a arranged in the rear side of the strip 9. The upper stop-member 32 preferably consists of a vertical 45 screw engaging an opening in a horizontal rail 35 mounted on the member 9 and having a padded button 36 adapted to be struck by the finger on its up-stroke. The lower stop-member 32 preferably consists of a vertically-swinging 50 elbow lever pivoted to the member 9 at 37 and having its padded upper arm arranged to limit the down-stroke of the sticker. Engaging the lower arm of this lever is a horizontal adjusting screw 38 having at its rear end a padded button 39 which bears against said arm. These several 55 screws 38 engage openings in the lower portion of the member 9, or other suitable support just above the channel board 10, and their headed front ends are accessible from the front side of the pneumatic action through the space left between the uppermost row of valve-blocks 12 and the strip 7.

60 65 By means of the adjusting screws 32 and

88, the stroke of the several stickers 28 can be conveniently regulated, as required, without removing the pneumatic action or any other parts.

Each of the striker pneumatics is preferably provided with a follow-up spring 40 which tends constantly to swing its movable board upwardly toward its fixed board, thereby keeping the movable board in contact with the button of the corresponding 75 sticker and preventing lost motion between these parts when the pneumatic is collapsed. It will be understood that in adjusting the sticker vertically by the screw 38, to bring its shoulder 30 in proper relation to the 80 wippen 3, the button of the sticker would ordinarily be raised and supported by the elbow lever 33, out of contact with the movable board of the pneumatic, in which case there would be lost motion between the button and said board and the latter would be relieved from the weight of the sticker or equivalent part of the action. The follow-up spring 40 is so light as to be overcome by the weight of the sticker, and yet strong 90 enough to constantly raise and press said movable board against the button of the sticker in the expanded or vented condition of the pneumatic. The spring thereby affords the advantage of automatically taking 95 up any such lost motion, and no adjustment thereof is required. In its preferred form this follow-up spring is located at the hinge-end of the pneumatic and consists of a piece of spring wire extending obliquely across the 100 hinge-joint with its ends suitably secured to the fixed and movable boards, respectively, as shown in Fig. 7. This produces a neat, compact and inexpensive construction.

I do not wish to claim in this application 105 the unit or valve block 12 as the construction of the same forms the subject of another application for patent filed by me May 24, 1918, Serial No. 236,426.

I claim as my invention:

1. The combination of a pneumatic, a sticker actuated thereby and having a laterally-extending member provided with a free end portion, and stop-devices arranged above and below said free end portion for limiting the stroke of the sticker.

2. The combination of a pneumatic, a sticker actuated thereby and carrying a finger, a lever arranged in the path of movement of said stop-member for limiting its 120 stroke, and adjusting means for said lever.

3. The combination of a pneumatic, a sticker actuated thereby and carrying a finger, a vertically-adjustable stop for limiting the upward stroke of said stop-member, an elbow lever having one of its arms arranged to limit the downward stroke of said stop-member, and adjusting means engaging the other arm of said lever.

4. The combination of an upright chan-

nel-board, striker-pneumatics applied to the rear side of said board, corresponding valve-blocks applied to the front side of said board, stickers actuated by said pneumatics and having stop-fingers arranged above the striker-pneumatics, adjustable means for limiting the upward stroke of said stop-fingers, a row of vertically-swinging elbow-levers, having their upper arms arranged to 5 limit the downward stroke of said fingers, and a horizontal row of adjusting screws arranged above said channel board and engaging the lower arms of said levers, there being a space above the uppermost valve-blocks to afford access to said adjusting screws.

5. The combination of a pneumatic, a member having a guide slot, and a sticker actuated by said pneumatic and carrying a 10 laterally-extending guide-member the free end of which is arranged in said slot, said slot being arranged parallel with the sticker

and the side walls of the slot holding the guide-member against lateral displacement.

6. The combination of a sticker having a 25 projection, a pneumatic having a movable board engaging said projection to actuate the sticker, and a follow-up spring constantly acting on said movable board to cause it to follow up said projection and prevent lost motion, said spring being light enough to be overcome by the weight of the sticker and yet strong enough to raise said movable board when relieved from the weight of the sticker. 35

7. The combination of a sticker having a projection, a pneumatic having a movable board engaging said projection to actuate the sticker, and a follow-up spring tending constantly to collapse the pneumatic, said 40 spring extending obliquely across the hinge-joint of the pneumatic and connecting its fixed and movable boards.

CHARLES V. JAMESON.
